IGNITION DEVICE.

1,176,794.

Specification of Letters Patent. Patented Mar. 28, 1916.

Application filed August 21, 1915. Serial No. 46,619.

To all whom it may concern:

Be it known that I, HENRY W. UHL, a citizen of the United States, residing at Freeport, county of Nassau, and State of New York, have invented certain new and useful Improvements in Ignition Devices, of which the following is a specification.

My invention relates to ignition devices, that is, to devices for firing the explosive mixture in the cylinders of an internal combustion motor. My improved mechanisms include means for effecting the make and break in the primary circuit of the spark coil very rapidly, the rapidity of making and breaking the circuit being independent of the speed of the motor. While the contact is made and released very quickly, the parts may be so proportioned that contact is maintained for a sufficient time to enable the desired saturation of the coils to be obtained. My improvements also include devices for reversing the direction of the current in the primary circuit of the spark coil each time the circuit is opened and closed, to prevent deterioration of the contact points at which the circuit is completed.

More particularly, my invention comprises a normally open primary circuit for the spark coil including a spring contact which is positively forced against the stationary contact, to close the circuit by the action of a contact closing device which rotates always in the same direction and carries spaced projections which wipe across the spring contact. This contact maker is rotated by a spring connection with the timer shaft or other rotating element and is held periodically by the engagement therewith of some form of detent. During each pause of the contact maker, its driving spring gathers power and upon the release of the contact maker by the detent one of its projecting points is rapidly wiped across the spring contact, to close the circuit, by the action of the driving spring. A distributor arm, constantly rotating, engages contacts in a distributor of usual form, each time that the primary circuit is opened and closed, to close the secondary circuit of the spark coil through the spark plug in one or another of the motor cylinders in the well known manner.

In the preferred forms of my device, the primary circuit of the spark coil includes brushes which bear on oppositely-disposed segments of a rotating commutator at the moment the circuit is closed. By the rotation of the commutator the connections are reversed at each successive making and breaking of the circuit. The object of my invention is to provide improved devices of the character briefly referred to above.

In order that a clearer understanding of my invention may be had, attention is hereby directed to the accompanying drawings forming part of this application and illustrating certain embodiments of my invention.

In the drawings, Figure 1 represents a longitudinal section through one form of my device, in which a rotating commutator for reversing the circuit connections is employed, Fig. 2 is a transverse section taken on line 2—2 of Fig. 1, and showing diagrammatically the electrical connections of the primary spark coil circuit, Fig. 3 is a transverse section taken on line 3—3 of Fig. 1, Fig. 4 is a sectional view, illustrating a detail of construction and taken on line 4—4 of Fig. 2, Fig. 5 is a sectional view similar to Fig. 1 of a different form of construction, Fig. 6 is a transverse section taken on line 6—6 of Fig. 5, Fig. 7 is a transverse sectional view similar to Fig. 2, showing a further modification, and Fig. 8 is a detail view illustrating a form of detent and contact making device somewhat different from that shown in Fig. 7.

Referring to the drawings and particularly to Figs. 1 to 4, the shaft 1 is illustrated as pinned to a sleeve or coupling 2, which is adapted to be secured to the timer shaft, or other rotating shaft, of the engine. Shaft 1 extends upwardly through the boss 3, into the interior of the casing 4. Shaft 1 has a gear 5 secured thereon immediately above the bottom plate 6 of the casing. Gear 5 meshes with a pinion 7, rotatable on a fixed pin 8, mounted in the bottom plate 6 of the casing. A detent member 9 is also rotatably mounted upon pin 8 and is secured to pinion 7, to rotate therewith. A commutator, represented generally at 10, and having elec-

trically conducting segments 11, 11', separated by insulation 12, 12, is mounted above the detent 9, to rotate therewith. A spring contact 13 bears upon the upper end of the 5 commutator and constantly makes contact with the horizontal extension 11^a of the segment 11.

The circuit 14 contains the battery 15, primary coil 16 of an induction coil, and the 10 normally open contacts 17 and 18. Contact 17 is carried by an adjusting screw 19, extending through an insulating bushing 20, in the casing 4. The contact 18 is carried by a leaf spring 21, secured at one end to the 15 casing, as shown at 22. The other end of the spring is held against undue movement inwardly by a stop 23 integral with or secured to the inner surface of the casing.

Contact between contacts 17 and 18 is 20 made by the rotary contact maker 24, which is loosely mounted upon shaft 1. A spiral spring 25 is coiled within the interior of member 24, one end of the spring being secured to shaft 1, and the other end to member 24. This spring tends to rotate the contact maker in the same direction as that of shaft 1. Contact spring 21 has a portion curved inwardly, as shown at 26, which is wiped across successively by the projections 25 30 27 on contact maker 24, to press contacts 17 and 18 together.

The detent member 9 has a cylindrical surface and a pair of vertical recesses 28 formed at diametrically opposite points on 35 its periphery. As detent 9 rotates with pinion 7, recesses 28 engage successively with the noses or projections 27 formed on member 24. Member 24 is provided with surfaces 29 on each side of noses 27, which are 40 curved on the same radius as the cylindrical surface of detent 9. Accordingly as shaft 1 rotates, member 24 rotates therewith, because of the spring connection 25 between the shaft and member 24, until a curved surface 29 of member 24 contacts the periphery of detent 9. Member 24 is accordingly stopped and spring 25 is put under tension by the continued rotation of shaft 1. In 45 the rotation of detent 9, a recess 28 now comes in line with the adjacent nose 27 of member 24, the nose dropping therein. As the rotation of the detent continues, nose 27 is released from recess 28, whereupon spring 50 25 snaps member 24 forward rapidly, the nose 27 immediately in advance of that which has been in engagement with the detent wiping across lug 26 on the contact spring 21, contacts 17 and 18 being pressed together while nose 27 is passing over lug 55 26 and circuit 14 closed during this interval.

The circuit from battery 15 extends through binding post 30, to a brush 31 which bears against the surface of commutator 10. In the position of the parts shown in Fig. 60 2, the circuit is completed from brush 31

through commutator segment 11, to the spring contact 13, which constantly engages segment 11. Spring 13 is secured at its other end to contact screw 19, and accordingly the circuit extends from spring 13 through contacts 17 and 18 when the latter are closed, to the casing 4 and thence to ground indicated at g. The circuit is completed from ground g' to commutator segment 11' and thence through brush 32 and binding post 70 33, through primary coil 16 to battery 15. Commutator 10 rotates through one hundred and eighty degrees between each make and break of the circuit at contacts 17 and 18, so that, upon the next make and break 75 80 after that indicated in the figures as about to be made, commutator segment 11' will be in contact with brush 31 and segment 11 in contact with brush 32, reversing the connections of the circuit through the make and break device.

The rotary contact maker 24, together with boss 34 formed thereon, may conveniently be stamped or otherwise formed of steel or other metal. The detent member 9, 90 which coacts therewith, is preferably made of hard fiber, or the like, and may be provided with an integral sleeve or bushing 35, extending through pinion 7. The pinion, detent 9 and commutator 10 may be secured 95 together by a number of pins, one of which 36 is shown in Fig. 4, this pin electrically connecting segment 11' of the commutator with the boss 37 of the casing 6, against which it rests. As the casing is permanently 100 grounded through the shaft 1, etc., this provides the ground for segment 11', shown in Fig. 2 of the drawings at g'. The spring contact 13 presses on the upper surface of the commutator and constantly makes contact with segment 11, which is provided with a horizontal extension 11^a, as stated above. Pin 8, about which pinion 7 and commutator 9 rotate, may be screw-threaded at its upper end, and provided with a nut 38 in a recess 105 in the commutator. The slots 28 of the detent 9 are preferably sufficiently deep to prevent the end surfaces of projections 27 of the contact maker engaging the same and becoming worn, the edges of the slots 28 110 being rounded to engage the surfaces 29 of the contact maker smoothly, and to release the same smoothly.

The distributor arm 39 of fiber, or other insulating material, is mounted upon the upper end of shaft 1, to which it is secured by a pin 40. A distributor 41 of insulating material is mounted upon the upper surface of casing 4 and serves to fire the explosive mixture in the various cylinders of the motor in the usual manner, the distributor 41 having a central axial contact 42, which is constantly engaged by the brush 43 on the distributor arm 39, and a plurality of contacts 44, equal to the number of cylinders to 120 125 130

be fired, which are engaged in turn by the brush 45 on the distributor arm 39, brush 45 being electrically connected to brush 43. The contact 42 being in circuit with the secondary of the spark coil 16, circuit is closed in the usual manner through the spark plug of each cylinder when brush 45 engages the contact 44 connected with that particular cylinder, brush 45 engaging a contact 44 each time that the primary circuit is opened and closed at contacts 17 and 18, brushes 31 and 32 being at the same time in contact with commutator segments 11 and 11', or vice versa.

15 The boss 34 of member 24 and shaft 1, together with distributor arm 39 are connected by a spiral spring 46 which is wound in the opposite direction to the spring 25 within member 24, spring 46 being secured at one end to the boss 34 of member 24. The other end of spring 46 is provided with a loop 47, through which pin 40 extends. When the device is operating forwardly, pin 40 moves forwardly in loop 47, as each nose 25 27 of the contact maker is held by detent 9, the spring 46 rapidly following the pin when projection 27 is released by the detent, so that the end of loop 47 reengages pin 40, to prevent overthrow of the contact maker, or to prevent the following projection 27 of the contact maker striking too hard against the surface of detent 9. The main function of spring 46 is to take care of the proper alinement of contact maker 24 with relation to spaces 28 of the detent in case of a reversed rotation of shaft 1 and the contact maker because of a back fire. When shaft 1 runs backwardly, pin 40 pulls upon loop 47 of spring 46 and thus rotates contact maker 24 in the reversed direction, the spring drawing the contact maker rearwardly (that is, in a clockwise direction, referring to Fig. 3) until a surface 29 of the contact maker abuts against the periphery of detent 9. The contact maker is held in this position until a slot 28 registers with the adjacent nose 27, and the contact maker is released when the slot moves out of registry with the nose. The stored-up power in spring 46 now draws the contact maker rearwardly a short distance. If, now, shaft 1 starts going forwardly again, surface 29 of the contact maker will impinge against the cylindrical surface of detent 9, and nose 27 will fall into the next slot 28 which comes in registry therewith. If spring 46 were not used to draw the contact-maker rearwardly, as stated, when released by the detent on backward movement, nose 27 would, upon the contact maker starting forwardly again, drop into the same slot 28 from which it has just been released in its backward movement, and spring 25 would not have power stored up therein to draw the contact maker forward rapidly, to wipe over spring contact

21, when released from the slot 28. Thus it is seen that spring 46 insures proper alinement of contact maker 24 with respect to the slots 28, when the contact maker starts forwardly after having rotated rearwardly. 70

The contact maker, in moving backwardly, wipes over lug 26 of a contact spring 21, comparatively slowly, so as not to produce an effective spark, even if the commutator segments were in alinement 75 with their brushes at this time, which is not the case. This slow movement is because the impulse of spring 46, when the contact maker is released from the detent is not sufficient to carry the next nose of member 24 80 past lug 26, the nose 26 moving past the contact at the same speed as shaft 1, after the impulse referred to of spring 46 is exhausted. Also, the commutator segments will not be in line with their brushes when 85 contacts 17 and 18 are closed on reverse rotation of member 24, because the impulse backwardly, due to spring 46, when member 24 is released by the detent, is not so great, as stated, as the impulse forwardly, due to 90 spring 25, when member 24 is released. Accordingly the commutator segments are not in the same relative positions when contact is closed at 17 and 18, on backward movement, as on forward. 95

The form of my device illustrated in Figs. 5 and 6 may be used particularly when it is desired to drive the device from a shaft 48, running at magneto speed, instead of running the device from the timer shaft, as in the form of my device first described. Shaft 48 has a pinion 49 thereon, engaging with a gear 50, mounted on shaft 1', to which a distributor arm (not shown) is secured in the same manner as distributor arm 39 was previously described as being secured to shaft 1, in the form of my device first described. This distributor arm makes contacts within the distributor 41' in the same manner as previously described. Shaft 1' has a hub 51 thereon, on which are mounted a plurality of spring arms 52 having heads or end portions 53, arms 52 corresponding to the contact maker 24 of the form of my device first described. The casing 4' is provided with a sector 53 adapted to slide through a limited arc about the circumference of the circular casing 4', casing 4' having an opening at the top which is bridged across by sector 53, the latter having a slot 54 therein in which the adjacent edges of the casing are mounted. The contact screw 19' carrying contact 17' extends through insulating bushing 20' in the sector 53, and the sector is moved relatively to the casing to advance or retard the spark, an arm 55 being shown as mounted upon the sector for suitable connection for moving the sector. The spring contact 18' is carried by an arm 56, pivoted on a pin 57, carried by 125 130

4
lugs 58, secured to the sector 53. Arm 56 is pressed by spring 59, to normally hold the contacts 17' and 18' open.

A roller 60 is mounted on pin 57, and is contacted by each of the heads 53 of spring arms 52 in the rotation of shaft 1'. The engagement of each head 53 with roller 60 retards the rotation of arms 52 until the arm in contact with roller 60 has bent back-
wardly a sufficient amount to enable the same to pass roller 60. The spring action of the arm 52 which is thus released causes the arm to move forward rapidly, so that its head 53 rapidly wipes over the lug 26' on arm 56 to cause contact 18' to be pressed against contact 17', while head 53 is moving over curved lug 26'. Stiff springs 61 are secured on the rear sides of arms 52, to prevent the latter swinging forwardly too far.
20 Heads 53 on spring arms 52 are suitably curved, so that the spring arms will be held back and bent rearwardly when the heads of the same contact roller 60, the elasticity of the spring arms causing the same to spring forwardly to wipe across curved surface 26' as each arm is freed from the roller. Heads 53 are given an easy curvature on their rear surfaces to enable the same to readily pass over the roller when the device is rotated rearwardly.
25 In this form of my device, the elasticity of the spring arms 52 is depended upon to furnish the impulse necessary to make the rapid contact-closing, the spring arms being secured to hub 51 which is secured to shaft 1'.
30

The commutator 10', which is mounted upon and rotates with shaft 48 is the same as commutator 10 mounted upon pin 8 in the form of my device first described. The 40 commutator is provided with a segment which is grounded in the same manner as segment 11' in the form of device first described, and a second segment 11 with which spring contact 13' constantly engages.
45 Spring contact 13' is mounted upon a screw 62, insulated from the casing and joined by connection 63, to the contact screw 19'. The electrical connections are practically the same in this form of my device as in that 50 first described, and accordingly are not shown. That is to say, the primary circuit extends through a binding post, as 30, and through a suitable brush to segment 11 of the commutator, thence through contact 55 spring 13' and connection 63 to contact screw 19', and through contacts 17' and 18', when the latter are closed, through lever 56 and the casing to ground, and thence to the other segment of the commutator and out 60 through the other binding post 33 to the primary coil, and thence to the battery, in the same manner as was described in connection with Fig. 2, the direction of current being, of course, reversed, when the commuta- 65 tor segments are in reversed position from

that described. There being two segments on the commutator, and four arms 52 in the form of device illustrated, the commutator segments rotate through one hundred and eighty degrees, to reverse the battery connections, each time that contact is made and opened between contacts 17' and 18'.
70

Another modification of my device is shown in Fig. 7. In this form, the rotary contact maker 24' having lugs or projections 27' thereon, is loosely mounted upon shaft 1², similar to shaft 1, illustrated in Fig. 1, and is connected for rotation from the same by a spiral spring similar to spring 25 shown in Fig. 3. A disk 64 is secured to shaft 1² to rotate therewith, and has a number of curved recesses 65 in its periphery. A detent lever 66 is pivoted at 67, within the casing 4². This detent lever has a curved end 68 which rides on the periphery of disk 64, being held in contact therewith by a spring 69. At the other end of the lever is a nose 70 adapted to be contacted by the lugs 27' on contact maker 24' in the rotation of the latter. When a lug 27' abuts against nose 70, the contact maker 24' is held until in the rotation of disk 64, a recess 65 thereon comes in line with the curved end 68 of the detent lever, end 68 dropping into the recess 65, immediately withdrawing nose 70, 95 and permitting contact maker 24' to be rapidly drawn forward by its spring, whereupon the projection 27' immediately following that which was held by the detent wipes across lug 26² on the contact spring 21', to 100 rapidly make contact between contacts 17² and 18². The circuit is closed while contacts 17² and 18² are pressed together, the elasticity of spring contact 21' causing a rapid break of the circuit as soon as the contact 105 maker has passed over lug 26². In this form of my device, no means for reversing the circuit connections is shown, the device merely opening and closing the circuit of the primary coil, which circuit is normally 110 open at the contacts 17², 18². It is to be understood that the distributor arm and distributor are connected and operated in the same manner as was described in connection with Fig. 1, and also that a spring similar to the spring 46 shown in Fig. 1 may also be used and connected in the same manner as there described for acting as a spring stop, and rotating the contact maker rearwardly if the timer shaft 1² should be rotated in a reversed direction.
115

Fig. 8 illustrates a detail modification of the above in that a detent lever 66' pivoted at 67' is used in place of the detent lever 66. In this construction, the 125 spring contact 21² is mounted directly on the detent lever and carries a contact 18³ adapted to be pressed against contact 17³ on the contact screw 19³. The contacts are normally held in open position by a 130

spring 71 which may be coiled about the pivot 67 and appropriately secured as to tend to rotate the lever in a left handed direction, referring to Fig. 8. The lever 5 has a curved lug 68 thereon, adapted to ride upon the periphery of the disk 64, shown in Fig. 7, and to drop into the recesses 65 therein. The nose 70' of the lever intercepts the projections 27' of the contact maker successively and holds each of the same until the nose 68' of the lever drops into a recess 65, whereupon the actuating spring of the contact maker (similar to spring 25 of Fig. 3) carries the contact maker rapidly forward, the lug 27' thereof, which has just been released from nose 70' wiping across a lug 26³ on the lever to force contact 18³ into engagement with contact 17³. In other respects this modification of my invention is 10 the same as that illustrated in Fig. 7.

It is evident that the curvature of the lugs 26, 26', 26², and 26³, in the various forms of my invention illustrated, may be so chosen as to increase or decrease the period of contact 15 between the contacts in the primary circuit, so that the desired saturation of the spark coil may be secured. It is also obvious that all of the forms of my device described provide a rapid make and break of the circuit, 20 which is constant for all the speeds of the motor, since the rapidity of the make and break is dependent upon the force of a spring which is stressed the same amount each actuation. All the forms of my device 25 operate on open circuit, so that a comparatively small current is used. The motion of the contact maker is rotary always in the same direction, during the operation of the igniter, the wear and jarring of a reciprocating contact maker being avoided. The provision of the devices for reversing the 30 circuit connections in the primary circuit, each time the circuit is opened and closed, is useful in preventing deterioration of the contacts at which the circuit is opened. It 35 is also obvious that the spring arms 52 in Fig. 6 perform the same function as the spring 25 in Fig. 3 and other forms of my device, in connecting the contact makers, 40 which may be considered as the heads 53, to the actuating shaft of the device, the force 45 of the spring being increased, in each instance, while the contact maker is held by the detent. When the contact maker is released from the detent, it is drawn forwardly to wipe across the spring contact 50 with an acceleration, due to the force of the spring, which may be uniform in all instances, and which is independent of the 55 speed of the motor.

It is to be understood that the contact maker, such as 24 (or 52; 53) has the proper number of noses 27, (or 53, or 27') to correspond with the number of cylinders to be fired.

It is to be understood from the above description that my invention is not limited strictly to the exact forms of construction illustrated, but that the same is as broad as is indicated by the appended claims.

Having now particularly described my invention, what I claim and desire to protect by Letters Patent is as follows:—

1. In an ignition device, the combination of a normally open circuit, including an electrical source, the primary of an induction coil, and a pair of contacts, one of which is spring-pressed away from the other, and has a curved lug movable therewith, a revolvably mounted contact maker, 75 having projections adapted to wipe across said lug, to momentarily close said circuit, a rotating shaft, a spring connecting said shaft and contact maker, and a detent adapted to engage each projection of the 80 contact maker in turn, hold the same while the force of said spring increases, and then release the same, to permit one of said projections to rapidly wipe over said lug, to press said contacts together, substantially as 85 set forth.

2. In an ignition device, the combination of an electrical circuit, including the primary of an induction coil, a source of current, and a pair of contacts, a rotating shaft, 95 a commutator rotating with said shaft, a rotary contact maker, actuated from said shaft, and adapted to press said contacts together periodically in its rotation, and means for periodically holding said contact maker, releasing the same, and causing the same to move past said contacts, to momentarily press at an accelerated speed, said contacts together, segments of said commutator being included in said circuit when the latter is closed, and said commutator being so connected and rotated as to reverse the direction of the current in said circuit each time the circuit is closed and opened, substantially as set forth.

3. In an ignition device, the combination of a normally open circuit, including an electrical source, the primary of an induction coil, and a pair of contacts, one of which is spring-pressed away from the other, and has a curved lug movable therewith, a rotating shaft, a series of revolvably mounted contact making surfaces, adapted to wipe across said lug, to momentarily close said circuit, spring means connecting said shaft and surfaces, and a detent, adapted to engage each said surface in turn, hold the same while the force of its connecting spring means increases to a predetermined amount, and then release the same, to permit one of said surfaces to rapidly wipe over said lug to press said contacts together, substantially as set forth.

4. In an ignition device, the combination of a normally open circuit, including an

electrical source, the primary of an induction coil, and a pair of contacts, one of which is spring-pressed away from the other, and has a curved lug movable therewith, a rotating shaft, a detent member connected to said shaft for rotation therefrom, and having recesses in the surface thereof, a rotary contact maker loose on said shaft, and spring-connected thereto, having surfaces 5 adapted to contact said detent, to be held thereby momentarily, and to enter said recesses, in the rotation of said detent, to be thereby released, and spring-actuated into wiping engagement with said lug, a distributor arm rotating with said shaft, and a distributor having contacts passed over by said arm, substantially as set forth.

5. In an ignition device, the combination of a shaft normally rotating in one direction, a rotary contact maker loose on said shaft, a spiral spring connecting said shaft and contact maker, adapted to rotate said contact maker in the same direction in which said shaft normally rotates, detent means 10 adapted to periodically hold said contact maker while said spring gathers force, and then release the same, a primary spark coil circuit, including normally open contacts, adapted to be momentarily closed by said 15 contact maker each time the same is released by said detent, and a spiral spring having a loop at one end, said spring being secured to

said contact maker at one end and connected to said shaft by a pin inserted in said loop at the other end, said spring being wrapped 35 in the opposite direction to said first spring, substantially as set forth.

6. In an ignition device, the combination of a shaft normally rotating in one direction, a rotary contact maker loose on said shaft, a spiral spring connecting said shaft and contact maker, adapted to rotate said contact maker in the same direction in which said shaft normally rotates, a gear on said shaft, a pinion meshing therewith, a detent and commutator rotating with said pinion, said detent being adapted to hold said contact maker periodically while said spring gathers force, and then release the same, and a primary spark coil circuit including normally open contacts, adapted to be momentarily closed by said contact maker each time the same is released by said detent, and brushes bearing on said commutator, the segments of the latter being included in said circuit, and being adapted to reverse the current direction in said circuit each time said contacts are closed, substantially as set forth.

This specification signed and witnessed this 18 day of August, 1915.
